UNITED STATES PATENT OFFICE.

FRANK W. WOOD, OF BROOKLYN, NEW YORK, AND HARRIS LANING, OF PETERSBURG, ILLINOIS; SAID WOOD ASSIGNOR, BY MESNE ASSIGNMENTS, TO CHARLES CORY & SON, INC., OF NEW YORK, N. Y., A CORPORATION OF NEW YORK.

SHIP'S TELEGRAPH.

1,163,191.

Specification of Letters Patent.

Patented Dec. 7, 1915.

Application filed August 8, 1910. Serial No. 576,232.

To all whom it may concern:

Be it known that we, FRANK W. Wood and HARRIS LANING, citizens of the United States, residing at Brooklyn, in the county of Kings and State of New York, and Petersburg, in the county of Menard and State of Illinois, respectively, have invented new and useful Improvements in Ships' Telegraphs, of which the following is a specification.

Our invention relates to a telegraph of that type in which a predetermined fixed series of intelligences may be transmitted from one point to another on shipboard, and more particularly to one of those systems in which use is made of step by step devices for transmitting and receiving signals. It is particularly adapted for use on shipboard and will be described as used thereon. While of the particular relation and adaptation stated however, our invention may readily be used in part or as a whole in connection with other systems, and in other situations. The transmitter of our invention is intended for use in transmitting signals from the bridges of vessels to the engine rooms and return. Heretofore telegraphs have been used for this purpose which have proven very satisfactory as long as the apparatus was in order. Breakdowns due to one cause or another are not uncommon however, and until the apparatus is repaired great inconvenience results, and accidents due to these causes are not unknown.

The object of our invention is to avoid these inconveniences, and liability to accidents, and to produce a transmitter which will be reliable under practically all conditions of service.

In the accomplishment of our invention we provide a transmitter with means for transmitting signals or intelligences both mechanically and electrically at the same time. We provide a simple actuating means for positively operating the two sets of signals simultaneously so that at all times one is a check upon the other. Thus when one system is operated the other must necessarily operate and thereby we eliminate the danger or probability of having the operator, through inadvertence or negligence, disconnect one system from the other and there-

by ignore the principle of having a check on the signals.

The further aim of our invention is to construct a transmitter so as by reducing the number of separate parts there are relatively few operative parts whereby to produce a simple structure which may be economically manufactured and will occupy but very little space.

The above and other objects of this invention may be accomplished by the structure hereinafter described in detail and shown in the accompanying drawings wherein,

Figure 1 is a front elevation of the transmitter. Fig. 2 is a section of the same taken on line 3—3 of Fig. 1. Fig. 3 is a front elevation with the cover removed.

The numeral 18 designates a box or casing, cylindrical in this instance. The particular transmitter shown is adapted to signal speed changes from the bridge to another part of a vessel and for this purpose the front of the casing is provided with a dial 19 on which the indications are marked, as shown, "full", "half", etc., speed, both ahead and astern. Journaled axially in the rear of the casing opposite the dial is a shaft 20. On this shaft near the rear end of the casing is a pulley 21, and secured to the casing concentric with the shaft and between the pulley and the rear of the casing is a ring 22 of insulating material carrying on its interior face two series of contacts 23, and 24, and between them a contact ring 25. Each of the contact members in the series of contacts 23 and 24 is adapted to be separately connected to respective electrical indicators at the receiving station, while the contact ring 25 is connected to a common return wire of the electrical system. The connection with the mechanical system is made from the pulley 21 of the transmitter by a chain or belt passing around said pulley, as is usual in mechanical signaling means. Secured to the adjacent side of the pulley 21 is a block 26 of conducting material carrying three contact fingers 27 yieldingly pressed into contact with the respective contacts 23, 24 and 25, and adapted to complete electrical circuits from the central ring contact to the series of contacts on either side of it. Also journaled in the casing of the transmitter is a second shaft 28 fixed in pro-

longation of shaft 20 and freely movable with respect thereto, having its adjacent end loosely journaled in the sleeve 29 on the shaft 20 and its other end journaled in the front of the casing. This shaft carries a pulley 30 of the same form as pulley 21 inside of the casing while on its other end it carries a pointer 31 adapted to move over the dial of the transmitter. A chain or belt 35 is adapted to be received by said pulley 30 whereby the same may be rotated from a receiving station so that the signal or order may be repeated back to the transmitter and indicated on the dial by the pointer 31 to show that it has been properly received. An operating handle 32 is connected to the end of the shaft 20 at the rear of the casing, and is provided with a pointer 33 which overhangs the front of the casing and the dial. When the pointer 33, by means of the handle 32, is moved from the "stop" indication to a position pointing to another indication on the dial, which latter indication is desired to be transmitted, both the electrical and mechanical transmitting means are actuated simultaneously. Should one system become disabled the other one would transmit uninterrupted, and as pointed out, it is obligatory upon the operator that he actuate both of the transmitting systems so that he cannot negligently or wilfully rely upon only one of the systems and disregard the other.

What we claim is:

1. In an apparatus of the class described the combination of mechanical transmitting signal means having a chain, an electrical transmitting signal means having a plurality of fixed independent electrical contact terminals, and a fixed common terminal,

of a shaft, a pulley keyed on said shaft adapted to receive said chain whereby to actuate said mechanical transmitting means, a plurality of contact fingers mounted on said pulley and rotatable therewith and adapted to engage said fixed terminals, one of said contact fingers being adapted to engage with said common terminal, and a handle on said shaft for turning the same and the pulley whereby to positively actuate both of said signal means simultaneously.

2. In a signaling apparatus of the class described the combination with a mechanical transmitting means having a chain to operate the same, and electrical transmitting means having fixed contact terminals, and a fixed common contact terminal, of a casing within which all of said terminals are circularly arranged, a shaft in said casing, a handle on said shaft for turning the same, a pulley in said casing keyed to said shaft for the reception of said chain to actuate the same, and a plurality of contact fingers mounted on said pulley to turn therewith and adapted for engagement with said terminals, one of said fingers being adapted for engagement with said common terminals.

In testimony whereof we have hereunto set our hands in presence of two subscribing witnesses.

FRANK W. WOOD.
HARRIS LANING.
